UNITED STATES PATENT OFFICE.

JOHN B. WALSH, OF BROOKLYN, NEW YORK, ASSIGNOR TO MERGENTHALER LINOTYPE COMPANY, A CORPORATION OF NEW YORK.

KEYBOARD MECHANISM.

Application filed May 21, 1928. Serial No. 281,757.

This invention relates to keyboard mechanisms, and more particularly to the kind now in general use in the commercial linotype machine, or as illustrated in the U. S. Letters 5 Patent No. 530,931, to P. T. Dodge, dated December 18, 1894. As employed in such machines, the keyboard mechanism ordinarily comprises a series of pivoted power-driven cam yokes adapted to actuate a series of vertical reeds or bars, which in turn operate escapements controlling the release of the matrices from their storage magazine. In practice, it sometimes happens that the movement of an escapement is resisted by a matrix 10 in improper position in the magazine, or for other reasons, and in such event it is desirable that the parts may yield so as to prevent their breakage or undue strain thereon. It has therefore been the custom to form the 15 cam yokes with open vertical slots, which allow them to shift vertically with relation to their pivot rod, and to provide spring-actuated plungers which stand above the yokes and hold them yieldingly upon the pivot rod 20 (see the Muehleisen Patent, No. 1,056,355).

The foregoing construction, however, is not altogether free from objection, as the parts are somewhat uncertain in their action, due to the tendency of the plungers to stick 25 or bind, and for other reasons unnecessary to refer to. In addition, the parts are expensive to manufacture, and much time and labor is required to assemble them and obtain their proper adjustment.

The present invention is intended to obviate these and other objections and contemplates a cam yoke which in itself will have the required resiliency to take care of any resistance offered to the movement of the escapement actuating devices. In the preferred embodiment illustrated, the cam element which operates the yoke is resiliently mounted therein so as to be capable of yielding relatively thereto when the yoke is subjected to undue resistance.

In the accompanying drawings, the invention has been shown merely in preferred form and by way of example, and as applied to the keyboard mechanism of a linotype machine of the class stated, but obviously many changes and variations may be made therein, and in its mode of application, which will still be comprised within its spirit. It is

therefore to be understood that the invention is not limited to any specific form or embodiment except in so far as such limitations are specified in the claims. 55

Referring to the drawings:

Fig. 1 is a vertical section through the front portion of a linotype machine showing the keyboard mechanism and parts controlled thereby with the present improvements applied thereto; 60

Figs. 2 and 3 are detail views showing the operation of the improved cam yoke; 65

Fig. 4 is an enlarged elevation, partly broken away, of the improved cam yoke;

Fig. 5 is a top plan view of Fig. 4;

Fig. 6 is a transverse vertical section taken on the line 6—6 of Fig. 4; 70

Fig. 7 is a detail perspective view of the cam supporting lever;

Fig. 8 is an elevation, partly in section, showing a modification of the improved cam yoke; and 75

Fig. 9 is a transverse section taken on the line 9—9 of Fig. 8.

As shown in Fig. 1, the matrices X are released from their magazine A by the underlying escapements A¹ which are operated by the series of vertically movable rods or reeds B through the medium of the corresponding series of pivoted escapement levers B¹. The upward or active movements of the reeds, which take place in opposition to the light wire springs A² of the escapements, are effected by the horizontally disposed yokes or levers C arranged as usual in two banks or series, and with their inner ends in position to lift the reeds. At their opposite ends, the yokes are formed with the open vertical slots C¹ which fit over the transverse pivot rods C²; and, between their ends, the yokes are provided with the operating cams or eccentrics D rotatably mounted therein. The cams of each series are adapted to be rotated by the underlying power-driven roll E. Near their inner ends, the yokes C rest upon the pivoted trip dogs F which normally sustain them at such height that the respective cams D will just clear the rolls E, the cams, in this position of the parts, being restrained against rotary motion by their engagement with the fixed stop pins D¹ depending from the framework. However, when the dogs F are rocked 90

about their pivotal axes, the yokes are tripped 95

100

105

and the cams D allowed to drop into frictional contact with the underlying roll E, which thereupon rotate the cams and cause them to rock the yokes upwardly and operate the escapements in the usual manner. The rocking of the trip dogs F is controlled by the series of vertical keybars F¹ which are slidably mounted in the keyboard and operated by the finger key levers F². As so far 10 described, the parts and their mode of operation are or may be the same as those embodied in the commercial linotype machine and in themselves constitute no part of this invention.

15 According to the present invention, it is proposed to construct the yokes so that one of the two essential elements thereof, i. e., the lever C or its operating cam D, may yield in relation to the other and thus provide the degree of safety required in the operation of the keyboard mechanism when undue resistance is offered by the reeds.

In the embodiment illustrated in Figs. 1 to 7, the yoke or lever C, which is preferably 25 stamped out of sheet metal, is formed about midway its length (see particularly Fig. 7) with an open transverse slot C³ and at its lower edge near its inner end with a notch C⁴, the latter affording the clearance required for the associated trip dog F as the cam drops into engagement with the constantly driven roll E. The bottom of the slot C³ is curved on a given radius and the top thereof is formed by an overhanging lip C⁵.

30 The cam element D (see Figs. 3 and 5) is arranged astride the supporting lever C with its two side plates D² parallel and adjacent to the opposite side faces of the lever. The plates D² are connected together by means of a stay pin D³, staked and riveted therein, and which constitutes a rotary spindle for the cam element. Each of the plates D² is provided with a lateral stud d located opposite each other near the outer periphery thereof 35 and which are spaced far enough apart to clear the lever C when the cam element is rotated. If desired, the side faces of the lever C may be milled or grooved (as indicated in Figs. 4 and 7) to provide additional clearance for the studs d and permit the latter to be made slightly longer. These studs d are adapted to cooperate with the depending stop pins D¹ and the latter are made wider than heretofore (and hence are more substantial) 40 so as to engage both studs and arrest the cam squarely as it completes its cycle of rotation. The cam element D is also provided with a bearing thimble D⁴ in which the stay pin D³ is journaled and which seats in the curved bottom portion of the slot C³. The side flanges d¹ of the thimble fit flush 45 against the side faces of the lever C and are intended to sustain and guide the cam face-wise in the slot C³.

50 A small compression spring C⁶ arranged

in the slot C³ and interposed between the thimble D⁴ and the overhanging lip C⁵ tends constantly to hold the cam resiliently in normal operative relation to the lever. Preferably, the spring C⁶ is anchored at both ends 70 so as to obviate any danger of its displacement, the lip C⁵ being shaped to fit in the upper end of the spring and the thimble D⁴ being formed between its side flanges d¹ with a depression or seat d² in which the lower 75 end of the spring is confined (see Figs. 4 and 6). As thus arranged, the cam is free to rotate in the thimble D⁴ but, at the same time, is capable of yielding in the slot C³ relatively to its supporting lever C and against 80 tension of the spring C⁶. These springs C⁶ are made considerably stronger than the corresponding escapement springs A², before mentioned, so that the resistance offered by the latter, under normal conditions, will be 85 insufficient to cause yielding of the cams D in relation to their respective supporting levers. If, for any reason, however, a reed should be blocked against upward movement, the corresponding cam will then be allowed 90 to yield and to complete its cycle of rotation without damage to the parts (see Fig. 3).

The improved device is very simple, inexpensive to manufacture, and in itself is capable of affording the resiliency required under abnormal conditions. Moreover, the lever C and the cam D may be quickly assembled and dissembled, one with or from the other, by merely inserting or removing the compression spring C⁶. The open slots C¹ 95 in the pivoted ends of the levers C are advantageous because they facilitate the independent removal of the cam units, it being noted (see Fig. 1) that the solid cross bars G, employed to retain the levers pivotally engaged 100 with the rods or wires C², are hinged mounted so that they may be swung out of the way when desired.

Attention is now directed to Figs. 8 and 9 which show the invention in a modified form. 110 In this instance, the yoke or lever C embraces the cam D as heretofore, and the latter is formed with a centrally located aperture D⁵ wherein is arranged a bearing thimble D⁶ which fits snugly in the curved lower end of 115 the aperture and has its side flanges d³ astride and flush against the side faces of the cam D. The thimble D⁶, although similar in form to the thimble D⁴ and formed with a depression or seat d⁴, is journaled on 120 the pivot stud C⁷ which is fixedly secured in the yoke C. A compression spring D⁷, anchored to the seat d⁴ and confined in an upper branch portion of the aperture D⁵, tends 125 constantly to hold the cam resiliently in place, that is, with the lower end of the aperture D⁵ in snug engagement with the flanged thimble D⁶. This particular arrangement likewise provides for the yielding of the cam D relatively to the yoke C whenever the 130

normal operation of the yoke is impeded, the peculiar shape of the aperture D^5 allowing free movement of the cam substantially in all directions with reference to the bearing 5 thimble D^6 , from the moment it raises the yoke into contact with the reed until it passes free of the driving roll E . At such times, any danger of the spring D^7 losing its purchase on the thimble so as to become wedged 10 between the latter and the walls of the aperture is obviated by anchoring the spring to the seat d^4 .

Many changes and alterations will readily occur to those skilled in the art without departing from the scope of the invention. It should therefore be understood, as previously stated, that the invention is not limited to any specific form or embodiment except in so far as such limitations are specified in the 15 claims.

This application is a continuation in part of an application filed by me March 9, 1928, Serial No. 260,346.

Having thus described my invention, what 25 I claim is:

1. In a keyboard mechanism of the class described, the combination of an actuating reed, a yoke or lever pivoted fixedly at one end and having its opposite end arranged in 30 position to engage the reed, and a rotary cam resiliently mounted in the yoke so as to be capable of yielding bodily in relation thereto when undue resistance is offered by the reed.

2. In a keyboard mechanism of the class 35 described, the combination of an actuating reed, a yoke or lever element pivoted fixedly at one end and having its opposite end arranged in position to engage the reed, a cam element rotatably mounted in the yoke, and 40 resilient means interposed between the yoke and cam elements whereby one is allowed to yield in relation to the other when undue resistance is offered by the reed.

3. In a keyboard mechanism of the class 45 described, the combination of an actuating reed, a yoke or lever pivoted fixedly at one end and having its opposite end arranged in position to engage the reed, a cam rotatably mounted in the yoke, and resilient means 50 interposed between the cam and the yoke and carried by the latter, whereby the cam is allowed to yield bodily in relation to the yoke when undue resistance is offered by the reed.

4. In a keyboard mechanism of the class 55 described, the combination of a pivoted trip dog, means for rocking the latter about its pivotal axis, and a reed actuating device comprising a yoke or lever pivoted fixedly at one end and resting at its opposite end 60 upon the trip dog, and a cam element rotatably mounted in said yoke and consisting of a pair of cam plates connected together in parallel spaced relation to each other, said yoke being arranged between the cam plates

and formed with a notch to clear the trip 65 dog when the latter is actuated.

5. In a keyboard mechanism of the class described, a reed actuating device comprising a rotary cam element consisting of a pair of cam plates connected together in parallel 70 spaced relation to each other, a supporting yoke or lever arranged between the cam plates and wherein the cam element is rotatably mounted, and a spring interposed between the yoke and came for maintaining the latter resiliently in normal operative relation to the 75 yoke.

6. In a keyboard mechanism of the class described, a reed actuating device comprising a rotary cam element consisting of a pair of 80 cam plates connected together in parallel spaced relation to each other, a supporting yoke or lever arranged between the cam plates and formed with a transverse slot, a rotary spindle for the cam element rotatably mounted in said slot, and a spring arranged 85 within the slot and cooperating with the spindle for maintaining the cam element resiliently in normal operative relation to the yoke.

7. In a keyboard mechanism of the class described, a reed actuating device comprising a yoke or lever formed with a transverse slot, a thimble movably mounted in the slot, a rotary cam journaled in the thimble, and 90 a spring carried by the yoke for holding the thimble and cam resiliently in normal operative relation thereto.

8. In a keyboard mechanism of the class described, a reed actuating device comprising a 100 rotary cam element consisting of a pair of cam plates connected together in parallel spaced relation to each other, a supporting yoke or lever arranged between the cam plates and formed with a transverse slot wherein 105 the cam element is rotatably mounted, and a spring arranged within the slot for maintaining the cam element resiliently in normal operative relation to the yoke, said slot being open to permit the cam and lever to be readily assembled and dissembled, one with or 110 from the other.

9. In or for a keyboard mechanism of the class described, a cam supporting yoke or lever formed about midway its length with 115 an open bearing slot, as and for the purpose described.

10. In or for a keyboard mechanism of the class described, a cam supporting yoke or lever formed about midway its length with 120 an open bearing slot, and near the opposite end thereof with a notch in its bottom edge for the purpose described.

11. In a keyboard mechanism of the class described, the combination of an actuating reed, a yoke or lever pivoted fixedly at one end and having its opposite end arranged in position to engage the reed, and a rotary cam 125

resiliently mounted in the yoke, said cam being capable of yielding relatively to its axis of rotation when undue resistance is offered by the reed.

5 12. In a keyboard mechanism of the class described, the combination of an actuating reed, a yoke or lever pivoted fixedly at one end and having its opposite end arranged in position to engage the reed, a rotary cam, and a 10 bearing thimble therefor journaled in the yoke, the said cam being resiliently connected to the thimble to permit yielding of the former in relation to the yoke when undue resistance is offered by the reed.

15 13. In a keyboard mechanism of the class described, a reed actuating device comprising a rotatable cam, a supporting yoke or lever therefor; a bearing thimble for the cam journaled in the yoke, and a spring for holding 20 the cam and thimble resiliently in normal operative relation so that the cam may yield in relation to the yoke and thimble when undue resistance is offered by the reed.

25 14. In or for a keyboard mechanism of the class described, a composite keyboard cam element comprising a body portion provided with a central aperture, a bearing thimble

30 mounted in the aperture, and a compression spring for holding the parts resiliently in their normal operative relation.

15. In a keyboard mechanism of the class described, the combination of an actuating reel, a yoke or lever pivoted fixedly at one end and having its opposite end arranged in position to engage the reed, a rotary cam, and a 35 bearing thimble therefor journaled in the yoke, the said cam being resiliently connected to the thimble and formed with an enlarged aperture to enable it to yield relatively to the thimble substantially in all directions during 40 rotation.

16. In a keyboard mechanism of the class described, the combination of an actuating reel, a yoke or lever pivoted fixedly at one end and having its opposite end arranged 45 in position to engage the reed, and a rotary cam resiliently mounted in the yoke, said cam being capable of yielding relatively to its axis of rotation substantially in all directions when undue resistance is offered by the reed. 50

In testimony whereof, I have affixed my signature hereto.

JOHN B. WALSH.
